UNITED STATES PATENT OFFICE.

JULIUS N. CAYO, OF GARY, INDIANA.

MATCH HOLDER AND IGNITER.

1,293,032.

Specification of Letters Patent.

Patented Feb. 4, 1919.

Application filed March 14, 1918. Serial No. 222,373.

To all whom it may concern:

Be it known that I, JULIUS N. CAYO, a citizen of the United States, residing at Gary, in the county of Lake and State of Indiana, have invented certain new and useful Improvements in Match Holders and Igniters, of which the following is a specification.

My invention relates to improvements in 10 match holders and igniters.

One of the objects of my invention is to provide a match holder and igniter arranged to present a series of matches convenient of access and so constructed as to automatically 15 ignite the match by the act of withdrawing it from the holder.

Another object of my invention is to provide convenient means whereby the match holding containers may quickly be filled 20 with matches to replenish those used.

Other and further objects of my invention will become readily apparent to persons skilled in the art, from a consideration of the following description when taken in conjunction with the drawings, wherein:—

Figure 1 is an elevation of one form of the device, showing parts in section.

Fig. 2 is a plan view thereof with parts broken away.

Fig. 3 is an enlarged transverse section taken on line 3—3 of Fig. 4.

Fig. 4 is a perspective view of one of the match-holding clips removed from the base.

In all the views the same reference characters are employed to indicate similar parts.

In the embodiment herewith illustrated in the drawings, the clip-holding base is rectangular in outline and on each of its four 40 faces it presents two rows of matches, and in the center there is a depression or cup receiver, for a cup to contain burned matches, ashes, tooth picks, or the like.

The match-holding clips are removable, 45 from the grooves made in terraced ledges on each side of the rectangular pyramid.

The clips consist, each, of a strip of spring sheet metal, or the like, bent upon itself into a U-shaped formation, being wider at its 50 bottom or yoke end, the sides being brought nearer together at its confronting ends, as shown, to grasp the match nearest its midportion or upper end. The clips, when removed, are resiliently held open by the inherent elastic tension of the metal, and are yieldingly pressed together when inserted

in narrower slots or grooves in the clip holder.

In the act of lighting a match, it is drawn upwardly through the clip. At the narrowest space between the clip members, and just before the match leaves the clip, it makes contact with a suitable match igniting agency, which is presented by this part of the clip, and which may be of a 65 chemical or mechanical nature.

In the particular embodiment the quadrilateral pyramid 5 and its clip-holding parts are made of a single piece. The structure may be cast in the ordinary way of a crude 70 or relatively cheap material, such as cast iron, or the like, and finished to suit circumstances, or it may be die-cast, or made of a plastic material, such as porcelain. On each of its sides it contains a ledge 6, around 75 which may be presented lettering, for the purpose of advertising, and another similar ledge 7, and thereabove, a third ledge 8. In the upper surface, 9, there is a depression 10, for containing an ash-receiving cup 11. 80 The cup is preferably made separable so that it may be removed and its contents emptied without the necessity of inverting the body portion of the clip holding device. A series of grooves, or tapering slots, 12 and 85

13, are provided on each side of the holding device, such grooves being larger or wider at the bottom, as more clearly shown in Fig. 1. The grooves 13 are made in the terrace 8, while the grooves 12 are made in 90 the terrace 7, and each of the grooves is provided at each of its ends with tapered registering openings 14. These openings are tapered outwardly so that the clips 15 may easily and conveniently be inserted in 95 either end of the grooves, by entering them first in the openings 14. The clips are as long, substantially, as the main portion of the respective grooves in which they are to be placed. The clips are each made of a 100 strip of resilient sheet metal or equivalent material, bent upon itself to form confronting walls or legs 17 and 18, and an intermediate enlarged yoke or base portion 19. This base portion is wider than the upper 105 portion of the clip structure, or, in other words, the legs or walls 17 and 18 diverge from their closest approximating upper edges toward the bottom. The natural resiliency of the clip, when formed, and when 110 not restrained, separates the legs 17 and 18 from each other, so as to leave considerable

room therebetween for insertion of the matches 20, as shown in Fig. 3. When the clips are placed in the grooves 12 or 13, the grooves, being narrower at their top edges 5 than the clip at the contacting surface therewith, press the legs 17 and 18 closer together, so that the upper surfaces of the clip will yieldingly contact with the opposite sides of the match 20 contained therein.

10 Located longitudinally of the clip, and on either side of the inner surface of each of the legs 17 and 18, is an igniting agency 21, which may be of a chemical nature for safety matches, or a roughened surface or 15 mechanical nature for the ordinary sulfur match.

When the clips are taken from the respective grooves to be filled with matches, they automatically spread apart for convenient 20 filling, and are then inserted into the tapered openings 14 prior to pushing them into the registering grooves. The openings 14, being tapered, will naturally compress the base portion of the clip, so as to bring the legs 25 17 and 18 closer together against the resilient resistance of the metal itself into contact with opposite surfaces of the matches 20.

Now it will be manifest, that when the matches are seized by their upper ends and 30 drawn, one by one, from the clips, that the head 23 of the match will be brought into contact with the igniting surfaces 21, thereby igniting the match just about the time when it leaves the clip. The tapered surface of the clip and its resilient contact with the inner surface of the groove prevents the 35 bodily displacement or removal of the clip when the match is lifted upwardly for the purpose of igniting and extracting it.

40 In Fig. 4, a match 25 is seen as it is lifted from the clip, showing it ignited. When the matches are placed in the clips, their heads rest upon the bottom surface thereof, as shown, and when they are lifted out of 45 the clips, they are not lighted until the head of the lifted match is considerably above the position of the heads of the undisturbed matches remaining in the clip, so that there is no danger or possibility of igniting the 50 matches remaining by the effect of the one that, at the time, is drawn from the clip.

After the clips have been withdrawn and filled with matches, it is only necessary to slightly compress one end near its base, and 55 insert that end into one of the tapered openings 14, and then by pushing, it will readily enter into the grooves 12 or 13, in either of which it is intended to be received.

The device, as shown in the accompanying 60 drawings, will hold in the neighborhood of 200 matches, which are adapted to be ignited as they are withdrawn from the match holding clip, one after another, without disturbing or igniting the matches remaining 65 in the clips.

The device, as a whole, may be used for advertising purposes, as indicated by the advertising matter placed upon the ledge 6, and other advertising matter, if desired, could be placed upon the ledge 9. 70

The device is intended especially for cigar stores, billiard halls, restaurants, and the like, although they may be made in different forms and provided with a more artistic character of ornamentation and used for 75 other purposes, and in different environments, and the clips may be used separately.

While I have herein shown and described in some particularity a special form which my invention may take, I wish it understood that it is not limited to the particular character and arrangement of the parts, its only limitation being measured by the 80 scope of the appended claims.

Having described my invention, what I 85 claim is:

1. A device of the character described comprising a base member having a groove wider at its bottom than at its top, and a match holding clip comprising two oppositely disposed resilient walls, normally spread apart and wider at the base part than the base part of the groove, said clip having a match igniting agency near the upper inner ends of the wall, whereby when the clip 95 is inserted in the groove the walls of the groove will be pressed together to engage the matches in the clip.

2. In combination with a compressible match-holding clip for containing a row of 100 matches and having a match-igniting surface near its free end, a clip holding base having a relatively narrow and shallow groove tapered from bottom to top so as to be wider at the bottom than at the top to 105 engage the sides of the clip near the bottom thereof to compress the clip against the stems of the matches, said base having an outwardly tapered opening leading to said groove to facilitate the insertion of said clip 110 therein.

3. In combination with a series of compressible U-shaped match holding clips, each adapted to contain a row of matches and having match-igniting surfaces near their 115 upper ends, a base of substantially quadrangular shape and having a plurality of ledges on each side, one above the other, each ledge having a U-shaped groove narrower at its top than at its bottom and having an outwardly tapering opening leading into these grooves, each groove being narrower than the normal width of the bottom part of its respective clip so that when the clip is inserted it will engage the sides thereof near 120 the bottom to compress the clip against the stems of the matches.

4. A device of the character described including in combination a base member of substantially rectangular shape, having a 125

plurality of ledges on each side, one above the other and having a central depression, each ledge having a substantially U-shaped groove narrower at its top than at its bottom and having an opening leading into each groove, a plurality of compressible U-shaped match holding clips, each one adapted to contain a row of matches and having match igniting surfaces near their upper ends, each groove being narrower than the

normal width of the bottom part of its respective clip so that when the clip is inserted it will engage the sides thereof near the bottom to compress the clip against the stems of the matches, the clips holding the 15 matches in a plurality of rows in different planes.

In testimony whereof I hereunto set my hand.

JULIUS N. CAYO.
